UNITED STATES PATENT OFFICE

2,473,536

DEVICE TO REPRODUCE TIMING DISKS

Harry Ephriam McCoy, United States Navy

Application September 18, 1944, Serial No. 554,690

1 Claim. (Cl. 90—15.1)

(Granted under the act of March 3, 1883, as
amended April 30, 1928; 370 O. G. 757)

1

This invention relates to duplicating machines and more particularly to improvements in machines for manufacturing precision indexes.

The invention is embodied in a duplicating machine of the type in which an index blank is clamped to a master index, the characters of which are to be reproduced on the blank and the blank and master index are rotated as a unit with respect to means for scoring the surface of the blank with characters similar to those on the master index. A suitable indexing device is provided for shifting the blank from position to position with respect to the scoring means between each cutting operation.

It is an object of the present invention to provide an improved machine of the type described which may readily be constructed with a minimum of equipment which requires a minimum of skill to operate and which is accurate and rapid.

It is customary in graduating indexes to divide the circumference of the index into major and minor divisions. The major divisions generally are demarcated from the minor divisions by extending the score lines further inward toward the center of the index. A feature of the present invention resides in means for selectively controlling the movement of the cutting means radially of the index blank to permit the formation of score marks of different lengths. As illustrated herein, the aforesaid means takes the form of limit stops operable to be moved into and out of the path of the movement of the cutting means to limit its movement radially of the index blank.

It is evident that the index blank and master index must be concentric in order accurately to duplicate the master index. It is a further object of this invention to provide means for clamping the index blank to the master index which is operable automatically to center the index blank and master index with respect to each other. Specifically, the aforesaid means comprises a four bar parallelogram linkage to one side of which is pivotally fastened, to two of the parallel links, the index blank and to the other side of which is fastened the master index and means for expanding or contracting the parallelogram.

A specific description of the construction and operation of the machine will now be described with reference to the accompanying drawings, in which:

Fig. 1 is a perspective view of a duplicating machine embodying my invention;

Fig. 2 is a front elevational view;

Fig. 3 is an end elevational elevation;

2

Fig. 4 is a plan view;

Fig. 5 is a perspective view of the preferred clamping means;

Fig. 6 is a front view in elevation of the clamp shown in Fig. 5;

Fig. 6a is a cross section of the clamping means at one corner;

Fig. 7 is a side view in elevation of the clamp shown in Fig. 5; and

Fig. 8 is a plan view of the clamp.

Referring to Fig. 1, the machine comprises in general, a base 10, a support 12 on which an index blank 16 clamped to a master index 14 may be rotated with respect to cutting means 18 and means 20 for rotating the index blank and master index as a unit with respect to the cutting means, the latter being adapted to be moved radially from an out of the way position across the index blank 16 to produce score marks corresponding to the score mark on the master index 14.

The base 10 preferably constitutes the top of a table or bench and supports the working parts of the machine at a convenient height from the floor.

The index blank 16 which is to be a duplicate of the master index 14 is clamped to the master index by spacing blocks 21 placed between the blank and the master index, counter sunk screws 22 being provided for fastening the plates to the opposite face of the blocks. The master index and index blank are placed upon the surface of the support 12 which consists of a plate 24 fastened to the upper end of a post 26. The post 26 is provided with a base 28 which is fastened to the base 10. The index blank and hence the master index are held in position on the plate 24 for rotation about the center of the index blank on pin 25 which projects upwardly from the center of the plate and is adapted snugly to engage a central aperture 27 formed in the index blank. A coating of grease is applied to the surface of the plate 24 to reduce friction between the bottom surface of the index blank 14 and the surface of the plate 24. Adjacent to the master index, there is fastened to the base an upright 30, the upper end of which is bent over at 32 to overlie the characters on the master index, the end of the bent over portion 32 being brought to a point. Thus the master index may accurately be aligned for each cutting operation. In order to turn the master index relative to the pointer 32 and to the cutting means 18, there is provided a rubber tired disc 34 mounted on a horizontal spindle 36 in a position frictionally

to engage the upper peripheral surface of the index blank 16. The spindle 36 is journaled in a pair of vertical spaced plates 38 fastened to a block 40 which in turn is secured to the base 10. The outer end of the spindle 36 is provided with a hand wheel 42 by which the disc 34 may be rotated thereby to turn the index blank and master index about the axis of the pin 25.

The means 18 for cutting the score marks on the surface of the index blank to correspond to the characters on the master index comprises a disc saw 43 attached to a spindle 44 which is driven by an electric motor 46, the latter being mounted on slide 48 which is mounted for movement transversely of the base 10 on a pair of parallel rails 50. The disc saw 43 is so positioned with respect to the plate 24 that when the slide 48 is reciprocated transversely of the base 10 on the rails the disc saw 43 will move to and from the center of the plate 24 and hence will make a radial score mark on the index blank supported on the plate 24. The rails 50 are attached to the base 10 by screws 52.

In the manufacture of index plates, it is customary to divide the circumference of the index plate into units of ten degrees and then to subdivide these units into units of five degrees and degrees. In order to distinguish the divisions, the larger divisions are denoted by long score marks while the smaller units have correspondingly shorter score marks. It is a feature of the present invention to provide means to facilitate producing score marks of different length for the purpose set forth above. To accomplish this, the slide 48 is yieldably held near the forward edge of the base 10 by a spring 54 and is moved rearwardly to cause the circular saw 43 to travel radially over the surface of the index blank 16 by a cord 56 attached to the rear edge of the slide 48, the cord being passed around a pulley 58 journaled on a vertical post 57 projecting upwardly from the base 10, beneath the slide 48, around a pulley 60 and downwardly to a pedal 62 which may be depressed by the operator to pull the cord downwardly and hence to pull the slide rearwardly in opposition to the spring 54. The pedal 62 is pivoted at 64 on the base 10. The pulley 60 is mounted on a spindle 66 which is journaled between a pair of angle arms 68 fastened to the front edge of the base 10. In accordance with the invention, in order to make long score marks, such as would be used to define ten degree divisions, a limit pin 70 is mounted in a block 72 fastened to the base 10 in a position to lie in the path of movement of the slide 48, thereby to limit the rearward movement of the slide 48 so that the disc saw 43 will always move the same distance inwardly of the blank when the treadle is depressed. Hence it is only necessary for the operator to depress the treadle 62 and then to release it in order to produce a score mark for a ten degree division of the proper length. In addition to the limit pin 70, there are provided limit pins 74 and 76 for the five degree and degree marks, respectively. These limit pins are slidably mounted in the block 72 at the near side of the limit pin 70, and are operable to be moved into and out of the path of the slide, thereby to limit the rearward movement of the support 48 by different amounts. The limit pin 76, which is for limiting the movement of the slide and hence the disc saw for five degree marks, is attached for operation to one end of a rod 78, the opposite end of which is pivoted at 80 on the base 10. Intermediate the ends of the rod 78,

there is pivotably attached a link 82 which in turn is pivotally connected to an operating rod 84. The operating rod 84 is pivoted at 86 to the base and its free end extends forwardly of the machine and is bent over at 88 to afford a convenient means for grasping it for operation. The limit pin 74 is likewise operated, being connected to a rod 90 which is pivotally fastened at 92 to the base 10. A link 94 is connected to the rod 90 at one end and at its opposite end to an operating rod 96 pivoted at 98 on the base 10. The free end of the operating rod 96 is bent over at 100 to afford means for grasping and operating it. For the convenience of the operator and to differentiate the two operating rods 84 and 96, a plate 102 is fastened to the base 10 beneath the operating rods and is marked with indicia denoting in which direction to move the operating rods and which of the limit stops will be actuated by each rod.

While the index blank 16 is shown clamped to the master index 14 by a pair of spacing blocks 21 and screws 22, this means of joining the index blank and master index is not entirely satisfactory since it takes considerable time to align the index blank and master index in perfectly concentric relation. Accordingly, another important feature of the invention resides in means for clamping the index blank and master index in such relation that they may automatically be brought into concentric relation. This is accomplished herein, by a clamp 104 (Fig. 5) consisting of bars 106, 108, 110 and 112 joined together at their ends into a four bar parallelogram linkage. Bolts 114 are provided for joining the ends of the bars in overlapping relation. The bolts 114 are adapted to be slidably received in radially disposed slots 118 formed in the master index. Threaded openings 120 are formed centrally of each of the bars of the linkage and are adapted to receive screws 121 by which the index blank 16 is clamped to any two of the parallel bars of the linkage, after the linkage has been brought into concentric relation therewith by adjustment of the parallelogram. Provision for this adjustment is made by a screw 126 which is threaded through a block 124 fastened to the master index in such a manner as to move radially inward or outward of the master index. The inner end of the screw 126 is fastened to a bracket 128 which in turn is fastened to one corner of the parallelogram and a handle 130 is fastened to the opposite end of the screw for rotating the screw, thereby to expand or collapse the parallelogram.

In making a duplicate index, the operator takes an index blank 16 of the proper size and fastens it to the master index 14 by means of the blocks 21 as indicated in Fig. 1 or preferably the parallelogram clamps in Figs. 5 to 8, inclusive, and then places the blank over the pin 25 on the surface of the plate 24. The hand wheel 42 is then rotated until the master index is turned to bring the zero mark on the index opposite the pointer 32. The electric motor is then started and the treadle 62 is depressed to move the slide readily into engagement with the stop 70 and hence to move the disc saw 43 inwardly to score a mark on the index blank 16 corresponding to the zero mark on the master index 14. Since the next mark on the master index is a degree mark, the operator then swings the rod 96 to the left which places the limit pin 74 in the path of a support 48 and again depresses the treadle 62 whereupon the slide moves rearwardly into engagement with

the stop 74 and a degree mark is made corresponding in length to the degree mark on the master index. After four of these degree marks are produced, a five degree mark is produced, by swinging the operating rod 96 to the right thereby to remove the limit pin 74 from the path of the support 48 and moving the limit pin 76 into the path of the slide by movement of the operating rod 84 to the left. It is apparent that the entire index of the master index may be reproduced on the index blank by continued rotation of the index blank and master index degree by degree until the index blank has been rotated through a full three hundred and sixty degrees.

The invention described herein may be manufactured and used by or for the Government of the United States of America for governmental purposes without the payment of any royalties thereon or therefor.

What is claimed is:

A machine for manufacturing precision indexes comprising a master index, an index blank upon which the master index is to be reproduced, said index blank and master index being fixed in superposed relation, a support adapted to receive the index blank for rotation in a horizontal plane, a friction disc rotatable about a horizontal axis, said friction disc being arranged so that its peripheral surface engages the surface of the index blank, means for rotating the friction disc to effect rotation of the index blank, an index member fixed adjacent to the master index, a portion of the index finger overlying the peripheral edge of the index blank, a cutting disc, an electric motor having a shaft to which the cutting disc is fixed, a movable motor support to which the electric motor is clamped, a pair of rails upon which the motor support is adapted to slide, said

motor and shaft being so arranged that movement of the motor support on said rails will move the cutting disc radially of the index blank, yieldable means normally holding the motor support, and hence the motor and cutting disc in a forward inoperative position, a flexible member attached to the movable motor support and to a treadle the latter being adapted by actuation thereof to move the motor support rearwardly against the opposition of the yieldable means to cause the cutting disc to travel over the surface of the index blank, stops adjacent to the motor support for limiting the rearward movement of the motor support to different amounts and means for selecting one or the other of the stops and moving it into a position to engage the motor support as it is moved rearwardly.

HARRY EPHRIAM MCCOY.
